UNITED STATES PATENT OFFICE.

JOHN H. GOEHST, OF CHICAGO, ILLINOIS, ASSIGNOR TO FEDERAL ELECTRIC COMPANY, OF CHICAGO, ILLINOIS, A CORPORATION OF ILLINOIS.

COMBINED CANDLE BASE AND SOCKET FOR MINIATURE ELECTRIC LAMPS.

No. 830,708.

Specification of Letters Patent.

Patented Sept. 11, 1906.

Application filed April 11, 1904. Serial No. 202,586.

To all whom it may concern:

Be it known that I, JOHN H. GOEHST, a citizen of the United States, residing at Chicago, in the county of Cook and State of Illinois, have invented certain new and useful Improvements in a Combined Candle Base and Socket for Miniature Electric Lamps; and I do hereby declare that the following is a full, clear, and exact description thereof, reference being had to the accompanying drawings, and to the letters of reference marked thereon, which form a part of this specification.

This invention relates to a novel holder for miniature electric lamps designed for attaching a miniature or low-candle-power lamp to a standard lamp-socket and so constructed that when fitted with a low-power lamp as to simulate the appearance of a candle, thus giving to an electric-light fixture fitted with a number of these devices a candelabrum effect.

The objects of the invention are to facilitate the connection of such a device with an electric-light bracket having a standard socket, to reduce the cost of manufacture, and to produce an exceedingly simple and durable device for the purpose specified.

The invention consists in the matters hereinafter set forth, and more particularly pointed out in the appended claim.

In the drawings, Figure 1 is a partial side elevation of the lower part of a chandelier, showing one arm thereof and my improved attachment applied thereto. Fig. 2 is a similar view showing the attachment in section.

It is often desirable on festive or other occasions to substitute for the usual full sixteen or other standard candle-power lamp a smaller lamp set into an elongated socket having the general conformation of a candle, thereby giving a candelabrum effect to the fixture. Heretofore attachments of this character to chandeliers or brackets having the usual size or standard sockets to receive the ordinary candle-power lamps have been attended with considerable expense of time and labor, requiring the services of a skilled electrician to make the connection. It is the purpose of this invention to provide a device of this character which may be readily applied to a fitting having the usual size socket

and substituted for the standard candle-power required for general illumination.

As shown in the drawings, A designates a portion of an ordinary chandelier, upon the outer end of the arm A' of which is carried the usual socket A², which receives a lamp of ordinary or standard candle-power.

B designates an elongated body made wholly or in part of insulating material and having the general form of a candle. Said candle-shaped body is provided at its upper end with a socket adapted to receive a small-power lamp C and is formed at its lower end to provide a base B³ to enter the standard socket A². The said candle-body B is preferably made wholly of insulating material, such as porcelain, and is provided with two conductors extending from the lower to the upper end thereof. One of the conductors, as herein shown, consists of a metallic rod B', which extends through an axial opening in the candle-body and is provided at its lower end with a head b, adapted to engage the central contact-piece a of the socket A². The other conductor consists of a wire B², which extends through a longitudinal opening in the candle-body at one side of the axial opening which receives the conductor B' and is connected at its lower end with a metal ring b', which surrounds and is permanently fixed to the base end of the candle-body and has screw-threaded connection with an internal-screw-threaded metallic ring a' within the socket A² and constituting one of the terminals of said socket A'. The socket at the upper end of said candle-body is provided with an interior metallic screw-threaded ring b², with which the metallic screw-threaded ring of the base C' of the lamp C has screw-threaded engagement. Said ring b² is connected with the conductor B² of the candle-body. The ring b² of the candle-body socket constitutes one of the terminals of said candle-body and the other terminal thereof is formed by a disk or nut b³ at the upper end of the rod B'.

The lower or base end of the combined socket and candle-body fits within the standard socket, so that said combined candle and socket is adapted to be readily substituted in said socket A' for the usual lamp. With this construction it is possible without the necessity of employing a skilled electri-

cian to readily substitute for the ordinary illuminating-lamp small-candle-power lamps with the candle attachment shown. After the necessity for the subdued illumination 5 has passed the usual lamps may be readily applied to the fitting. It will be observed that the substitution of the small-candle-power lamp for the standard lamp, and vice versa, is effected without any liability of disturbing or deranging the electrical connections of either the attachment or the standard socket. Moreover, my improved fitting is much more economically constructed and installed than prior attachments for this purpose, even though it be intended as a permanent part of an electric-light fixture.

I claim as my invention—

A combined candle, base and socket for supporting a miniature incandescent electric 20 lamp comprising an elongated one-piece candle-shaped body made of a single piece of insulating material, and provided at one end with a base comprising an external-screw-threaded terminal ring fitted over the end of

said body and adapted for screw-threaded 25 engagement with the screw-threaded terminal ring of a standard electric-lamp socket, and a central terminal adapted for contact with the central terminal of said socket, said candle-body being provided at its other end 30 with a socket comprising an internal-screw-threaded terminal ring made smaller than the terminal of a standard socket to receive the base of a low-candle-power or miniature electric lamp, and with a central terminal 35 adapted for contact with the terminal of said small-candle-power lamp, and conductors extending through openings in said body for electrically connecting the rings and central terminals at the ends of said body.

In testimony that I claim the foregoing as my invention I affix my signature, in presence of two witnesses, this 7th day of April, A. D. 1904.

JOHN H. GOEHST.
